TYPE-WRITING MACHINE.

991,166.

Specification of Letters Patent. Patented May 2, 1911.

Application filed April 14, 1906. Serial No. 311,708.

To all whom it may concern:

Be it known that we, HARVEY A. MOYER and OSCAR C. KAVLE, citizens of the United States, residing at Syracuse, in the county of 5 Onondaga and State of New York, have invented a new and useful Improvement in Type-Writing Machines, of which the following is a specification.

This invention relates more particularly to 10 improvements in type bar bearings and in retracting or returning springs for the type bar actuating levers of typewriting machines.

One of the objects of the invention is to 15 produce a type bar bearing of thin, compact form which will reduce the lateral movement of the type bars to the minimum and thereby insure a more perfect spacing of the impressions, and which will work with little friction and will be durable and adapted for 20 long service without adjustment for wear, and which can be made with great exactness at the minimum expense and labor.

Another object of the invention is to provide springs for returning the type bars and 25 their actuating levers to the normal position which will work with the least possible friction and are so constructed and arranged that they can be separately adjusted to equalize the touch of the several key levers, and 30 so that the tension of the whole series of springs can be simultaneously adjusted to change the touch to suit different operators.

In the accompanying drawings, consisting 35 of two sheets: Figure 1 is a fragmentary sectional elevation of a typewriting machine embodying the invention. Fig. 2 is a fragmentary bottom plan view, partly broken away, showing the key levers and their returning springs. Fig. 3 is an enlarged fragmentary sectional elevation of the spring adjusting means. Fig. 4 is a plan view of one 40 end of the spring adjusting bar. Fig. 5 is a sectional view of the type bar segment and elevation of one of the type bars and its hanger. Fig. 6 is a fragmentary view of 45 the same parts, showing the hanger in section. Fig. 7 is a cross section thereof in line 7—7, Fig. 5. Fig. 8 is a similar view, on an enlarged scale. Fig. 9 is a detail section, on an enlarged scale, of the pivot screw 50 and spacing sleeve. Fig. 10 is an elevation of a type bar and hanger of modified form. Fig. 11 is a fragmentary sectional elevation thereof. Fig. 12 is a transverse sectional 55 elevation thereof in line 12—12, Fig. 10.

Like letters of reference refer to like parts in the several figures.

Referring to Fig. 1, A represents the frame of a typewriting machine, B one of the type bars which are pivoted on a segment or support C, and D one of the key levers for actuating the type bars. A front strike typewriter is illustrated in the drawings of the character disclosed in the Patent, No. 819,365, granted May 1, 1906, to H. A. 60 Moyer and E. G. Latta, and the type bar segment is arranged in upright position below the platen, and the actuating key levers are pivoted at their rear ends, extending forwardly beneath the segment, and their movement is transmitted to the type bars by auxiliary levers, one of which is shown at E, pivoted at their lower ends, connected to the type bars at their upper ends and having pin and slot connections f between their ends 65 with the key levers. It should be understood, however, that the improvements are not limited to this type of machines but are applicable to many other forms of typewriting machines. 70

In the construction of the type bar bearing shown in Figs. 5—9, which is now deemed preferable, each type bar B is pivoted to a hanger consisting of a flat-sided sheet metal body G and two flat sheet metal side plates 85 g riveted on the opposite sides of the body, and between which the offset segmental circular and flat-sided inner end or bearing portion of the type bar is pivoted. The type bar is also made of sheet metal and has the 90 usual type head at its outer end. The type bar and side plates of the hanger are machined and then hardened, after which they, and also the hanger, are ground, for instance, on a magnetic chuck, to insure absolutely 95 flat, smooth and parallel surfaces, and to make the type bar very slightly thinner than the hanger body, so that it will swing freely between the side plates of the hanger without appreciable lateral play. The hangers 100 can be secured in radial slots in the segment by a retaining plate g' and screws g'', or in any other suitable manner. In these respects the construction of the bearing is like that described in said patent. 105

Instead of pivoting the type bar to the hanger by a shouldered rivet, such as shown in said patent, a combined pivot-screw and rivet H, Fig. 9, is employed having a plain cylindrical shank, a head, preferably conical, 110

adapted to seat in a countersink in one of the hanger side plates, and a threaded end for screwing into a threaded hole in the other side plate. The threaded end of the 5 screw is preferably made concaved, or with a conical hollow, so that after the screw is driven into place in the hanger it can be expanded slightly with a punch to prevent it from working loose. A cylindrical spacing 10 sleeve I surrounds the shank of the screw and fits in the pivot opening i of the type bar. The spacing sleeve is originally made slightly longer than the thickness of the hanger body, and after hardening, its ends 15 are ground until they are parallel and the sleeve is exactly as long as the thickness of the hanger body. A convenient way to insure the exact length of the spacing sleeve is to punch a hole k, Figs. 5 and 6, in the 20 lower end of the hanger body to fit the spacing sleeve and place one of the sleeves in the hole and leave it there during the grinding of the hanger body, so that both parts are ground in one operation to absolutely 25 the same thickness. Each spacing sleeve is used with the hanger with which it is ground to preclude the possibility of using a spacing sleeve differing in length from the thickness of the hanger body, and this is ac- 30 complished by temporarily securing the sleeve I in the hole k of the hanger body by any suitable means until ready for use.

After the side plates are riveted to the body of the hanger the sleeve is inserted in 35 the pivot opening of the type bar and both are then placed between the hanger side plates and secured by the pivot screw. The type bar is ground very slightly thinner than the body of the hanger, one five-thousandths. 40 part of an inch thinner as nearly as possible, so that when the pivot screw is driven in the spacing sleeve will be pinched and held stationary between the side plates and will hold the side plates from actual contact with 45 but very close to the type bar and parallel with each other. When the parts are found to be perfectly matched, so that the type bar will swing freely in the hanger with the least lateral play, the concaved end of the 50 screw is expanded slightly in the threaded hole of the hanger to prevent the screw from working loose, but should the type bar be found to be either too thin or too thick for perfect movement the screw can be with- 55 drawn and the type bar replaced by one of the exact thickness required before the screw is expanded. Should the screw be accidentally expanded too much, or so as to cause friction between the type bar and hanger, it 60 can be forced back enough to relieve the friction.

The screw and sleeve made and applied as described is a marked improvement over a 65 shouldered rivet for it is difficult to make and harden such small rivets of the exact

length between the shoulders required to insure perfect freedom of movement of the type bar without lateral play in the hanger, and furthermore, great care must be exercised in riveting such a shouldered rivet, 70 even when of the exact dimensions, to prevent the side plates from pinching the type bar and causing more or less friction. As the perfectness of fit of the type bar cannot be discovered in this construction until after 75 the pivot is riveted in place, it is necessary to remove the rivets connecting the side plates to the body of the hanger in order to replace a defective pivot and much material, time and labor is wasted in producing per- 80 fect bearings.

The construction of the bearing herein described permits all of the wearing parts to be hardened, and all meeting surfaces, including the ends of the spacing sleeves, to 85 be ground true after hardening. The bearing occupies the least possible space and has less friction and is capable of longer service without adjustment than any bearing known to us of such compact form. 90

The several parts of the bearing can be constructed more exactly than in known constructions and assembled without the loss of any of the parts and with less labor than usual. Owing to the removability of the 95 pivot screws the necessity for freeing the riveted pivots by grinding with emery and oil after riveting up the parts, as is done in other constructions, is avoided, and this conduces to greater durability for the reason 100 that no emery is left in the pivot joint to cause excessive wear after the machines are placed in service.

Instead of the combined screw and rivet pivot an ordinary rivet could be used, or an 105 ordinary screw could be used without being expanded in place, but in using an ordinary rivet it would be impossible to tell when the type bar makes a perfect fit in the hanger until after riveting, and an ordinary screw 110 would be apt to work loose. Screws similar to that shown but not having the hollow end could be used, but such screws would be harder to rivet down and more liable to distort the side plates when being riveted. 115

The type bar is nearer free from lateral vibration than in any other bearing known to us having so little friction, except possibly the more expensive, cumbersome and fragile ball bearings, and yet as the type bar does 120 not actually contact with the side plates of the hanger the type head is usually capable of an extremely slight lateral movement and to reduce this to the minimum the side plates of the hanger are provided with guide exten- 125 sions L, Figs. 5 and 6, above and in front of the offset bearing and of the type bar, which form lateral supports for the type bar at the time it approaches the printing point. The bar only comes in contact with the guide 130

extensions when fully under motion and causes no appreciable friction. As the guide extensions are integral parts of the hanger side plates they are stamped and ground 5 without extra cost, and they in effect increase the bearing of the side plates on the bar to more than three times the diameter of the offset bearing end of the type bar. The guide extensions fit the bar the same as the 10 bearing portions of the plates but as they are so far removed from the pivot they reduce the lateral movement of the bar when at the printing point so much as to make it unimportant. The guide extensions are preferable 15 to a guide at the printing point because they are noiseless on account of being nearer to the pivot and absolutely aligned with the bearing portions of the side plates, and they will not cause the type head to 20 tremble at the instant it reaches the printing point.

The modified construction of the type bar and hanger, shown in Figs. 10-12, is a reversal of that described and the side plates 25 g^3 are riveted to the body of the type bar B' and pivoted to the flat-sided hanger G' by a screw H' and spacing sleeve I' similar to those used in the first construction. The hanger in this case is made slightly thinner 30 than the body of the type bar and has an upwardly and forwardly projecting guide extension L' which is adapted to enter between the side plates of the type bar when the latter is at the printing point, to prevent 35 lateral movement thereof. This construction has many of the advantages of the one first described; but the first one is considered better because the hanger body overhangs and protects the pivot from dust and 40 the type bar is of less weight.

The springs for returning the key levers and connected parts to their normal position after actuation are preferably constructed and arranged as follows, see Figs. 45 1-4: M represents a horizontal bracket or bar rigidly secured in any suitable manner to the rear portion of the frame A and extending from side to side thereof. The bracket is preferably formed with depending 50 front and rear flanges, the front flange being provided with vertical slots m in which the rear ends of the key levers are pivoted on a wire or rod m' passing lengthwise through the bracket and crossing the 55 slots. N represents the returning springs. They are all alike, consisting of strips of spring metal and arranged one longitudinally beneath each key lever. The rear ends of the springs are preferably bent upwardly 60 and engage in a slot n extending lengthwise in the under side of the rear flange of the bracket M , and from their upturned rear ends the springs extend horizontally forward, then downwardly under the pivoted 65 ends of the key levers and then forwardly

and upwardly to bear at their front ends against the under sides of the key levers. The horizontal rear portions of the springs have parallel side edges and abut against each other to prevent lateral movement. 70 The springs taper forwardly from their wide abutting horizontal portions and are provided at their front ends with upturned ears n' which embrace the key levers to prevent the disengagement of the springs therefrom. By shaping and securing the rear ends of the springs as described they bear against and mutually hold each other from lateral displacement and are not weakened by holes for screws or other securing devices. The springs could, however, be attached to the bracket in any other suitable way. O represents an adjusting bar for the springs N . The adjusting bar is preferably of angular cross section and is located beneath the horizontal parts of the springs and is secured so as to be adjustable vertically. A series of adjusting screws P work in threaded holes in the horizontal flange of the adjusting bar and bear at their upper 80 ends against the under side of the several springs N . By properly adjusting these screws the tension of the springs can be individually regulated as desired. In the construction shown, see Figs. 3 and 4, the ends 85 of the vertical flange of the adjusting bar project beyond the ends of its horizontal flange and enter vertical slots p in depending end portions p' of the bracket M , which slots form guides that hold the bar vertical 90 and allow it to be adjusted vertically. The horizontal flange of the adjusting bar is slotted near its ends at p^2 to engage the grooved heads of screws p^3 which are screwed into threaded holes in the bracket 95 M and serve to support and move the bar up and down. Thus by adjusting the screws P the tension of the springs can be individually regulated to exactly equalize the touch of the several key levers, while by raising 100 or lowering the adjusting bar by the screws p^3 the tension of the whole series of springs can be changed to suit different operators. The individual adjusting screws P preferably have hexagonal heads, as shown in Fig. 110 1-4, and after they are adjusted a thin strip or bar q is placed between the heads of the screws and the vertical flange of the adjusting bar, as shown in Figs. 1 and 2, to lock the screws from movement. The lock strip is 115 held in place by any suitable means.

It will be seen from Fig. 1 that the returning springs for the key levers contact with the levers and adjusting screws P substantially in straight lines passing through the pivots of the key levers, and this arrangement of the springs reduces the sliding friction between the springs and key levers to the least amount possible with a flat or leaf spring in actual contact with the lever, and 130

permits the use of a flat spring with its great range of adjustment with no more friction than would be caused by a helical spring with its limited adjustment. It will be understood that in separately adjusting the tension of the springs by the screws P , all of the screw points may not be exactly in straight lines passing through the pivots of the key levers and points of contact of the springs with the key levers, but the arrangement is such as to bring the points of the adjusting screws as nearly as possible in such straight lines.

The key levers are detachably pivoted in the machine in such manner that they can be removed without disturbing their springs M . This is accomplished in the machine illustrated by making the pivot wire m' for the levers with a flat side and providing the key levers with circular pivot openings of the diameter of the full round wire intersected by slots r in the upper parts of the levers which are just wide enough to permit the passage of the pivot wire when turned with its flat side parallel to the sides of the slots r . The pivot wire is provided at one end with a lever r' , Fig. 1, by which it can be turned. When the lever is in the position shown by full lines the key levers cannot be detached, but by turning the lever to the position indicated by broken lines the key levers can be depressed and drawn forward out of their seats without disturbing their springs N other than by slightly flexing them as the key levers are pushed downwardly to clear the pivot wire. The auxiliary levers E are preferably detachably pivoted in a similar manner.

We claim as our invention:

40 1. A type bar and hanger composed of two flat body parts of slightly different thickness, and a pair of flat side plates independent of said body parts arranged at opposite sides of said parts and rigidly secured to the hanger body, the type-bar having an offset bearing end pivoted between the side plates below an overhanging portion of the hanger body and adapted to swing between said side plates, substantially as set forth.

45 2. A type bar having a flat-sided part at its pivot end, a hanger having a flat-sided body part, a pair of flat side plates independent of and arranged at opposite sides of said type-bar and hanger body and rigidly secured to one of said flat-sided parts and pivotally connected to said other part, one of said flat-sided parts having a portion overhanging the pivotal connection to exclude dust therefrom, substantially as set forth.

50 3. A type bar having a flat-sided offset pivot end, a hanger having a flat-sided body with an offset portion overhanging the off-

set pivot end of the type bar, a pair of flat 65 side plates independent of said type bar and hanger body and rigidly secured to the hanger body and pivotally connected to the offset end of the bar, the side plates being extended from the hanger body to form an 70 open guide having parallel sides to receive the body portion of the bar when it approaches the printing point, substantially as set forth.

4. In a typewriting machine, the combination of a series of type bar actuating levers pivoted at one end, and a series of spring strips supported at points beyond the pivot ends of said levers and engaging the levers between the ends thereof, the contact points 80 of the springs with the levers and with the spring supports being substantially in line with the lever pivots, substantially as set forth.

5. In a typewriting machine, the combination of a frame, a series of key levers pivoted to the frame at their rear ends, a series of spring strips supported in rear of the pivoted ends of the key levers and connected to the levers in front of their pivoted 90 ends, the contact points of the spring strips with the levers and spring supports being substantially in line with the lever pivots, substantially as set forth.

6. In a typewriting machine, the combination of a series of key levers pivoted at their ends, a series of spring strips rigidly secured beyond the pivoted ends of the levers and operatively connected to the levers between the ends thereof, and a series of adjusting screws bearing against the spring strips between their ends, substantially as set forth.

7. In a typewriting machine, the combination of a series of key levers pivoted at 105 their ends, a series of spring strips rigidly secured beyond the pivoted ends of the levers and operatively connected to the levers between the ends thereof, and a series of adjusting screws bearing against the spring 110 strips between their ends, substantially as set forth.

8. In a typewriting machine, the combination of a frame, a series of key levers pivoted to the frame, a series of springs having one end of each seated in a groove in a fixed part of the frame, and a series of screws acting to hold the springs in their seats and for tensioning the springs, substantially as set forth.

9. In a typewriting machine, the combination of a frame, a series of key levers pivoted to the frame at their rear ends, a series of springs having their rear ends seated in a groove in a fixed part of the 125 frame, and a series of screws acting to hold the springs in their seats and for tensioning the springs, substantially as set forth.

10. In a typewriting machine, the combination of a frame, a series of key levers pivoted to the frame, a fixed part of the frame having a groove extending parallel with the key lever pivots, a series of springs having one end arranged at an angle to the body of the springs seated in said groove, and means acting to secure the springs in the groove and force the free ends of the

springs into operative contact with the 10 levers, substantially as set forth.
